Primary Examiner — Catherine A Tuttle(74) *Attorney, Agent, or Firm* — Fisher Broyles LLP(57) **CLAIM**

The ornamental design for an animal bubble maker, as shown and described.

DESCRIPTION

FIG. 1 is a top front and right perspective view of the animal bubble maker showing my new design;

FIG. 2 is another top front and right perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom plan view thereof.

The broken lines are included for the purpose of illustrating the portions of the animal bubble maker that form no part of the claimed design.

1 Claim, 8 Drawing Sheets(56)
